UNITED STATES PATENT OFFICE.

CHARLES E. SCRIBNER, OF JERICHO, VERMONT, ASSIGNOR TO WESTERN ELECTRIC COMPANY, OF NEW YORK, N. Y., A CORPORATION OF ILLINOIS.

TELEGRAPH-RECEIVER.

1,107,367.

Specification of Letters Patent. Patented Aug. 18, 1914.

Application filed November 28, 1911. Serial No. 662,845.

To all whom it may concern:

Be it known that I, CHARLES E. SCRIBNER, citizen of the United States, residing at Jericho, in the county of Chittenden and State of Vermont, have invented a certain new and useful Improvement in Telegraph-
Receivers, of which the following is a full, clear, concise, and exact description.

This invention relates to printing tele-
graphs and more particularly to a printing telegraph receiver in which the characters are selected by a combination of two im-
pulses received over either one or both of
two main line conductors and in which the
second impulse of a combination is never of
the same character as that of the first.

More particularly this invention relates to a printing telegraph receiver in which the character selecting impulses are received
from the distant station by a selecting apparatus, which apparatus has a receiving relay for each characteristic impulse and in which the first impulse of a combination of impulses energizes and locks up a selected
relay, which relay remains locked up until the printing operation has taken place.

Another object of this invention is to pro-
vide a printing telegraph receiver in which is provided a plurality of type magnets, each
type magnet being provided with two ener-
gizing windings, the energizing windings of each magnet being arranged in different
loops of a selecting circuit, the different
loops being closed by a plurality of relays in
the selecting circuit.

In the drawings—Figures 1 and 2 com-
bined illustrate diagrammatically a complete
receiving system and in which so much of
the mechanical details as are necessary to
understand the operation thereof are shown
in perspective.

In Fig. 1 is shown the main line conductors L^1 and L^2 connected to the selecting apparatus, the relays of which are designated
by the numerals 1 to 8 inclusive, relays num-
bered 1 to 6 responding only to currents of
certain polarity, as shown, while 7 and 8 re-
spond to all impulses over the correspond-
ing line. Connected to the front contacts of
the polar relays are a plurality of type mag-
nets which, as a matter of convenience, are
designated by a numeral corresponding to
the combination of polarized relays neces-
sary to select the same. For example, the
selection of magnet 12 requires the energiza-

tion of polarized relays 1 and 2, etc. These magnets are marginal in operation, that is, it requires a flow of current through both of their cumulative windings to effect opera-
tion. The windings of these type magnets 60 are shown as arranged in two loops, one loop, including, for example, the upper winding of the type magnets 12, 13, 14, 15 and 16, the other loop, including the lower winding of the type magnets 21, 31, 41, 51 and 61. It 65 will be noted that the upper loop of each group passes through the energizing wind-
ing of the unit relays 100, 101, 102, 103 and 104, respectively, while the lower loop of each group of type magnets is connected to 70 the back contacts of the unit relays, respec-
tively. The windings of the unit relays all terminate in contacts at the armature of the switching relay 105, which armature is di-
rectly connected to the source of current 106. 75 This switching relay 105 is in a circuit which includes the locking winding of the polar relays 1 to 6 inclusive and the resist-
ance 107, which resistance is in parallel with the armature 108 of the starter relay 109. 80 Briefly, an impulse arriving over one or both of the main line conductors passes through and energizes a selected one of the polar re-
lays, which in turn is locked up completing 85 a circuit through the upper loop of a selected group of type magnets, through a selected unit relay, the armature of the switching relay, to battery 106. This circuit also passes through the switching relay 105 and through the resistance 107 of the starter 90 relay 109 to ground. The switching relay is energized, attracting its armature, but the selected unit relay is quicker acting than the switching relay and completes a locking cir-
cuit for itself through its right-hand arma- 95 ture and directly to the battery 106 before the armature of relay 105 is attracted.

The second impulse of a combination is never identical with that of the first im-
pulse, so that the second impulse, when it 100 arrives at the selecting circuit over the main
line conductor or conductors, will energize
another one of the polar relays, completing
in this manner the lower loop of the se-
lecting circuit, which lower loop will in- 105 clude the lower winding of one of the type
magnets whose upper winding is included
in the upper loop, thereby completing a
circuit from battery 110, through the print- 110
starter relay 109, and initiating the print-

ing operation. The type magnets are grouped in a circle about the type shaft 201 as shown at the left of Fig. 2 and each is provided with an armature 199 extending inward into a position to contact with the arm 200 when the corresponding pair of windings is energized.

A sufficient description of the circuits and apparatus will appear from the operation of selecting a predetermined type magnet, the shift, space, reset and paper lift magnets.

Let it be assumed that the operator at the distant end of the line wishes to select 15 at the apparatus shown on Figs. 1 and 2 a type magnet to print the letter "A" on the paper or record medium. Let it be further assumed that the combination of impulses necessary to select this character is 20 composed of two impulses, the first impulse being positive over line L¹, and the second impulse positive over line L², the two impulses being separated by an interval of no current. The first impulse of the combination will pass through the energizing 25 windings of the line relays 1 and 2 to ground, through the armature of the neutral relay 7, only relay 1, however, becoming active. As a result of this impulse, the armature of relay 1 is attracted, completing 30 a circuit which flows from battery 106, through the armature of switching relay 105, energizing winding of unit relay 102, through the upper loop of the type magnets 35 16, 15, 14, 13 and 12, in series in the order named, armature and locking winding of the relay 1, switching relay 105, resistance 107, armature 117 of relay 114 to ground. Switching relay 105 attracts its armature 40 but the unit relay 102, being quicker acting than the switching relay 105, completes a locking circuit for itself directly from the battery 106, through its right-hand armature and winding before the circuit first 45 traced is broken at the armature of the switching relay. The second impulse of the combination follows the first after a short interval of time, passing through and energizing the polar relay 3, which attracts 50 its armature. This second impulse will not complete a circuit through the upper loop of a group of type magnets, as was the case with the first impulse, the path to the battery 106 being broken at the armature of 55 the switching relay. The circuit closed by this second impulse is, therefore, completed through the lower loop of a group of type magnets, which circuit may be traced from the battery 110, starter relay 109, left-hand 60 armature of the unit relay 103, through the lower windings of the type magnets 63, 53, 43, 23 and 13, in series in the order named, armature and locking winding of the polar relay 3, switching relay 105, to ground 65 through the resistance 107 and armature

117 of relay 114, and as the starter relay 109 attracts its armature the latter portion of the path of this circuit will be in parallel to ground through the resistance 107 and the armature 108. Relay 3 is locked 70 up by the circuit just traced and the shunting of the resistance 107 by the armature 108 will cause an increase in the flow of current through the upper and lower winding of the type magnet 13, this magnet 75 being the one having both its windings in the circuit traced. This type magnet will, therefore, attract its armature 199 raising the inner end thereof into the path of the radial arm 200 on the type shaft 201. 80 Starter relay 109 attracts its armature 111 completing a circuit for the stop magnet 202 and the printing magnet 203, which circuit may be traced from battery 112, armature 113 of the clearing-out relay 114, 85 spacing magnet 204, printing magnet 203, stop magnet 202, armature 111 of the starter relay 109, to ground. As a result of the closure of this last circuit printing magnet 203 attracts its armature 205. Stop magnet 90 202 attracts its armature moving the pawl 206 at the outer end thereof out from engagement with the ratchet 207 on the type shaft 201. Type shaft 201 starts to revolve 95 in the direction of the arrow shown, power being derived for this purpose from the motor 208.

At the upper end of the type shaft 201 is shown a type wheel 209, carrying thereon two rows of type, the upper row of type being the one from which characters are ordinarily printed. This type wheel is slideable on the shaft 201 and may be moved upward to bring the lower row of type into printing position by means which will be hereinafter described. This type shaft 201, when released by the pawl 206, will revolve until brought to a stop by the radial arm 200 contacting with the outer end of the armature of the energized type magnet, when it will 100 be brought to rest with the character on the type wheel, corresponding to the energized type magnet, in position to print a character 105 on the paper. When the radial arm 200 contacts with the outer end of the armature 115 of the energized type magnet, a circuit is completed which may be traced from battery 112, clearing-out relay 114, armature 199 of the energized type magnet, radial arm 200, to ground. The armature 113 of the clearing-out relay is attracted, breaking the circuit through the spacing, printing and stop magnets. Armature 117 is attracted, removing ground from the selecting circuit heretofore traced, which is thus returned to 120 normal. The armature 205 of the printing magnet is retracted by the spring 212 and the selected character is printed on the paper. When the armature 113 of the clearing-out relay reaches its front stop, a circuit 125 130

is closed through the retractor magnet 216, which may be traced from battery 112, through the retractor magnet, to ground. The retractor magnet by the pawl 217 on 5 the outer end of the armature thereof moves the type shaft 201 in the reverse direction, moving the radial arm 200 out of contact with the armature of the energized type magnet, thereby breaking the circuit which 10 has heretofore existed from the battery 112, through the clearing-out relay. All parts 15 of the device are therefore returned to normal in condition to receive another selecting combination of impulses. The paper carriage is moved forward step by step as the characters are printed as hereinafter described.

If it is desired to print a character shown on the lower row of the type wheel, a combination of impulses is sent from the distant station to energize, first, the polar relay 4 with the first impulse, and then the polar relay 6 with the second impulse. This combination of impulses will energize the 25 shift relay 46, one winding of which is shown on Fig. 1 and the other winding on Fig. 2, current for the winding shown on Fig. 2 being obtained from the source of current 120. As this relay is selected and energized in a manner analogous to the printing magnet as above described, a detailed description of the circuits is considered unnecessary. As a result of the selection of this relay, a circuit is completed which may be 30 traced from battery 112, clearing-out relay, 114, energizing winding of the shift lock relay 121, armature of shift relay 46, to ground. As a result of the closure of this circuit, the following occurs: Shift magnet 40 220 is energized from battery 219, through the locking winding and armature of shift lock relay 121, the armatures of back shift relay 36 and reset relay 26, to ground. Clearing-out relay 114 attracts its armature 45 117, removing ground from the selecting circuit of the shift relay 46, allowing the selecting circuit to return to normal. Shift magnet 220 attracts its armature and the roller on the outer end thereof moves the 50 type wheel 209 upward on the shaft 201 and into position to print the characters on the lower row thereof into printing position.

The shift magnet 220 will remain energized owing to the locking circuit above 55 traced and the subsequent characters selected will be those on the lower row of the type wheel until the locking circuit is broken either by the energization of the reset relay 26 or the back shift relay 36.

If it is desired to move the paper carriage 60 forward as in leaving a space between successive words or in paragraphing, a combination of impulses is sent from the distant station to select the spacing relay 16. The 65 selection of the spacing relay 16 closes a cir-

cuit through the spacing magnet 204, which may be traced from battery 112, armature 113, spacing magnet 204, slow-acting relay 122, armature of the space magnet 16, to ground. The spacing magnet is therefore 70 energized and by means of the ratchet and pawl 225 and 226 the carriage is moved forward through the space of one letter. The energization of the slow-acting relay 122 completes a circuit through the clearing-out 75 relay 114, from battery 112, through the armature of slow-acting relay 122, to ground, and the clearing-out relay 114, by its armature 117, removes ground from the selecting circuit of the spacing relay 16, allowing the 80 selecting circuit to return to normal.

The paper carriage is moved forward step by step as the characters are printed, and when it has reached the limit of its travel a combination of impulses is sent 85 from the distant station to energize the paragraph relay 56. It will be noted that in energizing this paragraph relay the reset relay 26 is energized simultaneously there- 90 with. Both relays attract their armatures with the following result: A circuit is closed which may be traced from battery 227, through the reset magnet 228, armature of reset relay 26, to ground. Armature of the reset magnet 228 is attracted, removing the 95 pawl 229 from engagement with the ratchet 230 and the paper carriage is returned to its normal or initial position under the influence of spring 231. When the paper carriage reaches its initial position it moves into en- 100 gagement with spring 232, moving this spring and the spring 233 into engagement with the springs 234 and 235, respectively. A circuit for the paper lift magnet 236 is thereupon completed from battery 227 which 105 may be traced from battery 227, contact springs 233 and 235, paper lift magnet 236, armatures of the paragraph relay 56 and the reset relay 26, to ground. The armature of the paper lift magnet 236 moves the mem- 110 ber 237 into engagement with the member 238, gripping the paper therebetween, and lifting it upward a sufficient distance to insure a clean surface for the next line of characters. When the armature of this pa- 115 per lift magnet 236 is fully attracted the extension 239 thereof moves contact spring 240 into engagement with the contact spring 241, completing a circuit for the clearing- 120 out relay 114, which circuit may be traced from battery 112, clearing-out relay 114, contact springs 241 and 240, to ground. The clearing-out relay 114 as before, sends the selecting circuit and all parts of the de- 125 vice back to normal condition.

If it is desired to reset the paper carriage at any point in its travel without at the same time energizing the paper lift magnet, a combination of impulses to energize the 130 reset relay 26 alone is sent from the distant

station. As before, reset relay 26 attracts its armature, energizing the reset magnet 228 from the battery 227, removing the pawl 229 from engagement with the ratchet 230 and the paper carriage is returned to its normal or initial position under the influence of the spring 231. As the paragraph relay 56 has not been energized the energizing circuit for the paper lift magnet will 10 not be completed by the springs 233 and 235. A circuit for the clearing-out relay will, however, be completed from the battery 112, through the contact springs 232 and 234, armature of the paragraph relay 56, 15 armature of the reset relay 26, to ground, sending the polar relay circuit and all parts of the device back to normal.

While I have shown on the drawings a plurality of batteries or sources of current, 20 it will be understood that where such batteries or sources of current are of the same character or potential and located at the same place, they may be and preferably are one and the same battery or source of current.

What I claim is:

1. In a printing telegraph receiver, the combination of a plurality of type magnets having two windings and arranged in 30 groups, one winding of each group of magnets being in a different loop of a selecting circuit, means comprising a plurality of relays for selectively energizing one loop of a group of type magnets in response to an impulse received from a distant station, a unit relay in the selecting circuit closing on its energization a locking circuit for itself, a second impulse received from a distant station operatively selecting one of the remaining line relays to close the second loop and initiate the printing operation.

2. In a printing telegraph receiver, the combination with a plurality of type magnets having two windings, one winding of 45 each group of type magnets being arranged in different loops of a selecting circuit, line controlled self-locking mechanism for successively closing break points in the selecting circuit in response to a combination of impulses received from a distant station to select a predetermined type magnet and initiate the printing thereof.

3. In a printing telegraph receiver, the combination of a plurality of polar line relays, of a plurality of groups of type magnets selectively energized by a combination of impulses received by the polar line relays from a distant station, a locking circuit for each of the polar relays, each included in 55 the selecting circuit of a group of type magnets, and operating to lock the selected line relays in operative condition, means operated by a selected type magnet to initiate the printing operation, and means operated 60 at the termination of the printing operation

to break the locking circuit through the selected line relays, whereby the line relays are returned to normal condition.

4. In a printing telegraph receiver, the combination with a plurality of type magnets, selecting circuits therefor, each selecting circuit comprising a plurality of loops, each loop passing through a different winding of the type magnets, and including a unit relay, a line circuit, polarized relays 70 therein successively operated to close different points in the selecting circuits, said selecting circuit for each group of type magnets including a locking winding for said relays, a printing means, and means operating on the completion of the printing cycle 75 to break the locking circuit of the energized line relays and the selecting circuit, whereby all parts of the device are returned to normal position.

5. In a printing telegraph receiver, the combination in a line circuit, of a plurality of polarized line relays therein divided into two groups, one group being connected to each main line conductor, each relay being 90 responsive to a characteristic impulse received from a distant station, and means for locking the selected line relays in operative position.

6. In a printing telegraph receiver, the combination of two main conductors, a line circuit, said circuit comprising two groups of polarized relays, one group being connected to each main line conductor, and each relay in each group being responsive to a characteristic impulse received over the main line conductors, a locking circuit for each relay operating to hold the said relay in operative condition, a plurality of type magnets selectively operated by a combination of 100 two impulses received by the line circuit, a printing magnet operated by said selecting circuit to print the character selected by the line circuit, and means operated on the completion of the printing operation to break 110 the locking circuit through the selected line relays, whereby all parts of the device are returned to normal position.

7. A selecting circuit comprising a plurality of marginal magnets each having two cumulative windings, both of which must receive current to cause operation, said windings being arranged in groups, means for selectively completing a circuit through a group of windings, and means for selectively establishing a circuit through a second group of windings, one of said second group being associated with the same magnet as one of the windings of said first group.

8. A selecting circuit comprising a plurality of magnets each having two windings, both of which must receive current to cause operation, said windings being arranged in groups, means for selectively establishing and holding a circuit through a group of 125

windings, means for selectively establishing and holding a circuit through a second group of windings, one of said group being associated with the same magnet as one of the windings in the first group selected, and means controlled by said second circuit for causing an increase in the flow of current through both circuits.

9. A selecting circuit comprising a plurality of marginal magnets each having two cumulative windings, both of which must receive current to cause operation, said windings being arranged in a plurality of groups, means for selectively establishing a circuit through all the magnet windings of a group, holding means for said circuit, and means for selectively establishing and holding a circuit through a second group of magnet windings.

20 10. A selecting circuit comprising a plu-

rality of magnets each having two windings, both of which must receive current to cause operation, said windings being arranged in groups, switching means, means for selectively establishing a circuit for all the magnet windings of one group through said switching means, means in said circuit for establishing a holding circuit through said group of windings, and means for selectively establishing and holding a circuit through a second group of magnet windings independent of said switching means. 25

In witness whereof, I heretunto subscribe my name this 21st day of November A. D., 1911.

CHARLES E. SCRIBNER.
